SECURITY APPARATUS FOR ARMORED CARS
Frederick Johnston, Jr., 406 N. Fairview,
Mount Prospect, Ill.
Filed Apr. 15, 1963, Ser. No. 273,136
15 Claims. (Cl. 180—82)

This invention relates to a new and improved security apparatus for armored cars.

Armored cars are employed to carry money and important documents from one location to another with a minimum chance of losing those articles. The term "armored" means that the car is provided with external plate to resist unwarranted entry into the interior of the car and further the car is usually equipped with arms to resist any felonious attack. The car is usually provided with at least two compartments with a substantial bulkhead between the driver's compartment and the vault or valuable carrying compartment. As a rule the armored car has a crew of two or three persons, one of which is the driver and the other two comprising a guard and a messenger. The armored car is thus equipped to transmit large amounts of money and negotiable instruments from and to banks, stores, businesses and to carry on this movement of valuables with a minimum of danger of having those valuables lost or stolen. However, in spite of numerous precautions, armored cars carrying large amounts of money have been subject to attacks and burglaries, and because of inherent weaknesses in the security apparatus available in armored cars, some of these attacks have been successful and large sums of money have been lost on a number of occasions.

It is a principal object of this invention to provide an armored car with a security apparatus built therein to substantially eliminate successful attempts at thefts of the contents of the armored cars.

An important object of this invention is the provision of a security system for armored cars in which the occupants or crew of the car may completely control the door operation and energize alarm mechanisms which should minimize, if not entirely do away with, successful hold-ups of armored cars.

Another important object of this invention is to supply a security apparatus for armored cars of the two compartment type in which there is included a three-unit electrical system having one unit located on the outside of the armored car, a second unit located in the first compartment of the armored car, and a third unit located within the second compartment of the armored car.

A still further important object of this invention is to equip an armored car with a security apparatus enabling the occupants of the valuable carrying compartment thereof to lock all doors of the vehicle from within, to impair the ignition system of the armored car and to energize an alarm siren or other loud noise making device.

A still further important object of this invention is to provide a security apparatus for armored cars having three spaced apart, electrical boxes for controlling entry into the armored car and exciting alarms.

Another and still further important object of this invention is to provide an electrical system for securing the contents of an armored car in the transmittal of valuables in which a first unit thereof located externally of the interior of the car may be actuated by a key only

2

after an alarm has been energized to permit access to the driver's compartment of the vehicle.

A still further important object of this invention is to provide a control panel within the driver's compartment to lock or unlock each of the doors of the vehicle and to provide for manual actuation of a switch controlling a siren alarm.

A still further important object of this invention is to provide a control panel in the valuables compartment in which the guard or messenger operating that electrical unit can similarly control the operation of all of the vehicle doors and in addition can with one switch cause all of the doors in the vehicle to remain locked, the ignition for the armored car to be cut out, and to energize a siren alarm.

Another important object of this invention is to supply a control mechanism in the vault compartment of an armored car which superimposes controls for the operation of any of the vehicle doors regardless of the existence of controls for the doors located elsewhere on or in the vehicle.

A still further important object of this invention is the provision of an armored car with solenoid-operated locks actuatable electrically and having no external hand or key operated latch means at the position of the doors.

Another and still further important object of this invention is to supply a weather-proof electrical control box located on the exterior of an armored car and requiring the opening of a cover which automatically excites an alarm mechanism for as long as the cover remains disengaged from the weatherproof box.

A still further important object of this invention is to equip an armored car with a weatherproof electrical control box on the top center of the hood of the engine of the armored car by which initial entrance to the interior of the armored car is effected.

Other and further important objects and advantages will become apparent from the disclosures in the following specification and accompanying drawings.

40 In the drawings:

FIGURE 1 is a side elevational view partially in section of an armored car having the security apparatus of the subject invention incorporated therein.

45 FIGURE 2 is a longitudinal sectional view of the first or externally located electrical control box of this invention.

FIGURE 3 is a perspective view of the second or driver's compartment electrical control box of this invention.

50 FIGURE 4 is a perspective view of the third or valuables compartment electrical control box of this invention.

FIGURE 5 is a diagrammatic sectional view looking down at the top of the armored car with the roof removed and diagrammatically showing the electrical circuits as incorporated within and around the armored car.

As shown in the drawings:

The reference numeral 10 indicates generally an armored car having the security apparatus of this invention mounted thereon. The armored car includes a chassis 11 with ground engaging wheels 12. An engine hood 13 conceals an engine (not shown) at the front end of the vehicle. The vehicle further includes headlights 14, a front bumper 15 and a rear bumper 16. The body of

the car is designated by the numeral 17 and is preferably made of heavy plate armor material to prevent unwarranted entrance to the interior and to aid in the resistance of attack by firearms or the like.

The armored car vehicle has a front or driver's compartment 18 and a rear or valuables containing compartment 19. A bulkhead 20 is disposed between the front and rear compartments and this bulkhead is also made of armor plate to prevent access to the rear compartment from the front compartment.

The front compartment is provided with a windshield 21 through which a driver is able to see to drive the armored car. The compartment also includes a driver's door 22 and a door 23 disposed opposite the driver's door. Both doors 22 and 23 on opposite sides of the armored car lead to the front compartment 18.

The rear compartment is provided with a side door 24 and a rear door 25. All of the doors 22, 23, 24 and 25 are spring urged to normally swing to a slightly open position. There are no external handles on the doors and no means on the outside of the doors to effect opening of those doors. However, as will subsequently be described, there is a control box outside of the car which enables the initial opening of either the driver's door 22, or the other front compartment door 23.

The driver's compartment is equipped with a steering wheel 26, a foot pedal 27 for the clutch and brake, a gear shift lever 28, and an ignition switch and lock 29 all of which enable operation of the armored car by a driver.

A window 30 is located in the driver's door 22 and it is preferably bullet-proof to further enhance the armored characteristics of the vehicle. Similar bullet-proof windows are provided for the other doors of the armored car. These are the windows 31 for the front door 23, the window 32 for the side door 24 of the rear compartment and a window 33 for the rear door 25 of the compartment 19. Another bullet-proof window 20a is provided in the bulkhead 20 to permit ready viewing between the front and rear compartments of the vehicle.

Hinges 34, 35, 36 and 37 are respectively provided for each of the doors 22, 23, 24 and 25 and preferably include therein the spring mechanism for automatically tending to open the doors a slight amount. When the doors are thus initially opened as will subsequently be described a member of the crew can then pull the door open fully about its hinge and get into the car.

A seat 38 is provided in and extends across the front compartment 18 for a driver of the crew and any other member of the crew assigned to the front compartment. The rear compartment has a seat 39 for a crew guard and a seat 40 for a crew messenger. The location of the seats in the rear compartment 19 and the fact of whether or not there is one or two occupants of that rear compartment will have no bearing on the operation of the security apparatus of this armored car.

The door 22 is provided with a lock or bolt member 41 which is adapted to lock the door from the inside. An electrical solenoid 42 is mounted on the door 22 and when energized is arranged and constructed to slidably withdraw the bolt 41 into the solenoid 42 to an unlocked position. The door lock is arranged so that upon the solenoid 42 being electrically energized the bolt 41 is pulled into the solenoid 42 thus permitting the door 22 to be opened about its spring hinge 34. It should be understood that the door locks may be manually operated from the inside to enable the crew to optionally open the doors either electrically or manually. There is no latch or lock operating mechanism located on the external sides of the doors 22, 23, 24 and 25, however when the lock or bolt 41 is removed from its car body engaging position the door may thus be pulled open from the exterior. It is preferable, as previously explained, that the spring loading of the doors be such that when the solenoids are activated and the locks are pulled out of the way the spring tends to open the door a slight distance allowing the per-

son entering the vehicle to grab the edge of the door and thus open it. This obviates the necessity of using external door handles, but this of course should be considered an optional construction and if it is desired to have external handles even though they are not capable of operating the locks within the doors, they could be used as pull means to open the doors if the springs in association with the hinges were arranged to normally urge the doors toward a closed position. A lock or bolt 43 is provided on the door 23 and this is operated by a solenoid 44. Similarly a lock or bolt 45 is provided on the door 24 and is operated by a solenoid 46. The rear door 25 has a lock or bolt 47 which is operated by a solenoid 48. It will thus be seen that each of the 4 doors of the armored car is electrically operated and thus the controls for the locks may be disposed in a central location or may be split or divided and placed in several locations, such as in the present invention as will subsequently be described.

A storage battery 49 is provided in the car and is positioned beneath the hood 13. The battery is employed to operate all of the car's electrical appliances, such as a starter motor, the headlights 14 and the electrically operated security apparatus of this invention. The security apparatus includes a first control box 50 preferably located centrally of and on top of the engine hood 13 at a position close to the outside of the windshield 21. The security apparatus also includes a second control box 51 located in the front compartment 18 of the armored car as shown in FIGURE 1. The control box 51 is mounted on the underside of the roof 52 of the body 17. A third control box 53 is located in the rear compartment 19 and is also mounted on the underside of the roof 52.

An audible alarm 54 such as an electric bell is located on the wall or ceiling of the rear compartment 19. This electric bell is utilized to advise personnel that someone is entering the armored car. This bell or audible alarm 54 is not primarily used to ward off an attack on the armored car, but rather merely is used to advise those people in the vicinity of the car storage area that someone is entering the car and the armored car is being readied for its service of transferring valuables from one location to another. Of course, the ringing of the bell 54 also advises anyone in the rear compartment that someone is about to enter the front compartment.

Under the engine hood 13 there is provided a loud audible electrical alarm such as a siren 55. Also under the hood is an engine coil 56 and an electrical distributor 57 for distributing electrical power to the vehicle engine, which has not been shown.

As best shown in FIGURE 2 a housing 58 is provided for the electrical control box 50. The inner end of the box 50 is identified by the numeral 59. A partition 60 is spaced forwardly from the inner end 59 and defines a rear chamber 61 within the box 50. A front cover 62 is spaced forwardly of and parallel to the partition 60 and defines a second or forward chamber 63 within the box 50. The space 63 is disposed forwardly of the space 61. A peripheral flange 64 is provided on the cover 62 for the purpose of snugly engaging the outside of the housing 58 of the box 50. A handle 65 is affixed to the front cover 62 and is used to effect manual removal or replacement of the cover on the housing 58 of the box 50.

The interior of the box 50 carries electrical components which cooperate with the other components of this invention to control the operation of the vehicle doors, the alarm mechanisms and the engine ignition. A micro-switch 66 is fastened to the inner end 59 of the box 50. Similarly a multiple-terminal connector or socket block 67 is also fastened to the inner end 59 at a spaced apart position thereon. A post 68 is fastened at a right angle to the front cover 62 and projects rearwardly for slidably movement through an opening in the partition 60 and terminates closely adjacent the micro-switch 66. A collar or washer 69 is mounted on the post 68 midway of its ends. A cross pin 70 is adapted to pass through

the post 68 and hold the collar 69 in fixed position on the post at least with regard to the movement of the collar toward the inner end of the post. A coil spring 71 surrounds the post 68 and is disposed between the partition 60 and the collar 69 thereby urging the post 68 toward its innermost position. An elongated shaft key 72 is provided in the lower side of the post 68 for engagement with a correspondingly shaped notch in the partition 60 to prevent rotation of the post and its integral front cover 62 relative to the partition and the housing 58.

Also enclosed within the box 50 is a toggle switch 73 mounted on the partition 60 and disposed within the front or second chamber 63. A key operated switch 74 is also mounted on the partition 60 and is disposed within the chamber 63 of the box 50.

In the operation of the device of this invention it is necessary to remove the cover 62 of the control box 50 in order to initially gain access to the interior of the armored car of this invention. This is accomplished by pulling the front cover 62 in the direction of the arrow 75 thereby causing the cover 62 to be disengaged from the body 53 of the box 50. This, of course, pulls the post 68 outwardly from the micro-switch 66 against the action of the coil spring 71 which by reason of its engagement with the collar 69 is constantly urging the post 68 into engagement with the micro-switch 66. A key 76 is used to operate the key switch 74 which becomes exposed upon the removal of the front cover 62.

As best shown in FIGURE 5 the micro-switch 66 includes spaced apart contacts 77 and 78. A cross bar 79 is provided for sliding movement in the micro-switch 66. A post 80 is affixed to the cross bar 79 and projects outwardly toward the cover post 68 of the control box 50. A coil spring 81 is disposed behind the cross bar 79 and normally urges the cross bar toward engagement with the spaced contact points 77 and 78. Thus when the front cover 62 of the box 50 is in position on the housing 53 the post 68 depresses the post 80 of the micro-switch thus holding the cross bar in disengagement with the spaced apart contacts 77 and 78 against the action of the spring 81. However, when the cover 62 is removed by a manual pulling on the handle 65 the post 68 is moved away from its engagement with the micro-switch post 80 thus permitting the spring 81 to push the cross bar 79 into engagement with the spaced contacts 77 and 78 thereby completing an electrical circuit which will later be described to excite the audible bell alarm 54 located in the vault compartment 19 of the armored car of this invention. A fuse 82 is disposed immediately behind the micro-switch 66 within the box 50 and thus insures the safety of the electrical elements of this invention as will be seen by a detailed description of the circuits provided herein.

The box 51 which is the second of the electrical control boxes of this invention and which is disposed within the driver's compartment 18 of the armored car includes successive switches 83, 84, 85 and 86 to control the solenoids of the doors 22 and 23 leading to the front or driver's compartment 18 and the doors 24 and 25 which lead to the vault compartment 19. The electrical box 51 also includes a siren switch 87 which is adapted to control or excite operation of the siren 55 located under the engine hood 13. The general arrangement of the switch elements on the box 51 is shown in the perspective view of FIGURE 3 which shows the box 51 detached from the apparatus of this invention. A plurality of sockets 88 are provided on the box 51 in the same manner as the plural sockets 67 on the box 50. The sockets 88 enable the box to be electrically connected by a cable and plug means from the preceding box to a succeeding box 53 which is located in the rear or vault compartment 19 of the armored car. The electrical control box 51 is provided with a socket 89 for the attachment of a cable to actuate the solenoid for operation of the driver's door 22. Similarly a socket 90 is provided on the other end of the box 51 to provide for the attachment of a cable to effect

operation of the solenoid in association with door 23 which is also used for gaining access to the front or driver's compartment 18 of the armored car of this invention.

As best shown in FIGURE 4 the third electrical control box 53 of this invention is provided with successive switches 91, 92, 93 and 94 to also control the solenoids for operation of the doors 22, 23, 24 and 25 respectively of this invention. The box 53 also includes a four pole-double throw switch 95 which is used by an attendant in the rear vault compartment 19 in the event of a felonious attack on the vehicle to insure the safety of the contents of the vault 19 and to prevent unwarranted removal of the vehicle from its present site. The electrical box 53 is also provided with a plural socket 96 to provide for its attachment by a multiple strand cable to deliver electricity from the boxes 50 and 51 and thereby join the entire electrical circuit to the source of battery energy at 49 as will subsequently be described. A special socket 97 is provided in the box 53 to enable the attachment of a cable for the operation of the bell 54. Similarly a socket 98 is provided in the box 53 for the attachment of a cable to actuate the solenoid for operation of door 24 leading to the vault compartment 19. A further socket 99 is disposed in the box 53 and is adapted to receive a cable for the actuation of a solenoid to operate the opening and closing of the rear door 25 also leading to the vault compartment 19.

As shown in FIGURE 5 the electrical circuit utilizes the grounding of certain of the electrical elements to complete the electrical circuit. A ground 100 is shown associated with the source of electro-motor force which in this instance is the storage battery 49. A lead 101 from the storage battery 49 carries the source of power to one side of the fuse 82. A lead 102 is attached to the other side of the fuse 82 and extends to the electrical contact 77 of the micro-switch 66 located within the electrical control box 50 which as previously stated is disposed externally of the interior of the armored car of this invention. Another lead 103 also attached to the other side of the fuse 82 carries the source of electrical power to a juncture 104. A lead 105 fastened to the juncture 104 extends to one side of the key switch 74. A lead 106 is fastened to the other side of the key switch 74 and extends to one side of the toggle switch 73. Spaced apart contacts 107 and 108 are provided in the toggle switch 73 and are the means of energizing the solenoids 42 or 44 and thus operating either of the doors 22 and 23 leading to the front compartment 18 of this vehicle depending upon the position of the toggle switch 73. A lead 109 is fastened to the switch 83 and to the contact 107 of the toggle switch 73. Similarly a lead 110 is fastened to the switch 84 and to the other contact 108 of the toggle switch 73. It will thus be seen that the contact or terminal 107 of the toggle switch 73 is associated with the switch 83 on box 51 within the interior of the front compartment 18 of the armored car which controls operation of the driver's door 22. Similarly the contact or terminal 108 of the toggle switch 73 is associated with the second switch 84 of the box 51 which has previously been stated to effect operation of the other front compartment door 23. A lead wire 111 extends from the junction 104 to the junction 112. A lead wire 113 is fastened to the junction 112 and joins a switch contact 114 of the first switch 83 on the box 51. As best shown in the circuit diagram of FIGURE 5 the switch 84 is provided with a switch contact 115 comparable to the switch contact 114 of the switch 83. The lead 113 similarly joins the switch contact 115 with the junction 112 in the same manner as it joins the junction 112 with the switch contact 114 with the switch 83. A lead wire 116 extends from the junction 112 and joins a switch contact 117 of the third switch 85 on the second box 51. Similarly this same lead 116 joins the junction 112 with the switch contact 118 of the switch 86. The lead 116 continues and is fastened to one terminal 119 of the loud siren alarm

55. The siren 55 is provided with a second terminal 120 which is joined by a lead wire 121 to a contact 122 on the siren switch 87 located on the second box 51 of this invention. A lead wire 123 continues from the switch contact 122 to a first switch 124 on the four pole-double throw switch 95 of the third electrical control box 53 located in the rear vault compartment 19 of the armored car of this invention. The switch 87 is provided with a ground 125 as shown in FIGURE 5. Similarly a grounding 126 of the first switch 124 of the multiple switch 95 is also shown in FIGURE 5. A blank contact 127 is provided on the other side of the first switch 124. Thus in one position of the four pole-double throw switch 95 the first switch thereof 124 will engage the ground and in its other position the switch 124 will engage a contact which is joined to no part of the circuit and thus is for convenience termed a blank contact 127.

A lead wire 128 extends from the first switch 83 on the box 51 to a terminal 129 on the solenoid 42 which is associated with the driver's door 22. A grounding 130 of the solenoid 42 is also shown in the circuit diagram of FIGURE 5. A lead wire 131 extends from the switch 84 to a terminal 132. The terminal 132 is located on the solenoid 44 associated with the other front compartment door 23 to therewith energize that solenoid when electrical current is admitted thereto to actuate the bolt member 43 and thus open the door 23. A grounding 133 of the solenoid 44 is shown in the circuit diagram of FIGURE 5.

A second lead wire 134 extends from the first switch 83 on the control box 51 to the switch 91 in box 53 located in the vault compartment 19. The switch 91 is provided with a contact 135 which is joined by a lead wire 136 to connect the switch 91 to a junction 137. The junction 137 is joined by a lead wire 138 running back to a junction 139 with the lead wire 116 which has direct connection to the battery 49 through the junction 112, lead 111, junction 104, lead 103, fuse 82 and lead 101 to the battery 49. Similarly a second lead wire 140 is provided from the switch 84 on the second box 51 to the second switch 92 on the box 53. A contact 141 is provided on the switch 92 which is joined to the lead wire 136 and thus is also joined to the source of electrical power of the battery 49.

A lead wire 142 extends from the switch 85 on the second box 51 to switch 93 on the third box 53. A contact 143 is provided on the switch 93 which is joined to the lead wire 136 in the same manner as are the contacts 135 and 141 of the switches 91 and 92 respectively. A lead wire 144 extends from the switch 93 to a third switch 145 of the four pole-double throw switch 95 located on the third electrical control box 53. A blank contact 146 is provided on one side of the third switch 145 while a contact 147 on the other side is joined to a lead wire 148 extending to a terminal 149 on the solenoid 46 for operation of the door 24 mounted on the side of the armored car and leading to the vault compartment 19. As shown in FIGURE 5 the solenoid 46 is provided with a ground connection 150.

A lead wire 151 extends from the switch 86 to the switch 94. A terminal 152 is provided on the switch 94 and it is joined to the lead wire 136 which as stated previously is joined to the source of electrical power which in this case is the storage battery 49. A lead wire 153 extends from the switch 94 to a fourth switch 154 of the four pole-double throw switch 95. On one side of this fourth switch 154 there is provided a blank contact 155 and on the other side there is provided a contact 156 which has a lead wire 157 running to a terminal 158 on the solenoid 48 associated with the rear door 25 of the vault compartment 19. The solenoid 48 is shown grounded at 159 in the circuit diagram of FIGURE 5.

A second switch 160 is provided on the four pole-double throw switch 95. A lead wire 161 joins this second switch 160 to one terminal 162 on the ignition switch 29. The second switch 160 is provided with a blank contact

162a on one side and is provided with a contact 163 on the other side thereof which has a lead 164 running to a junction 137 which through the lead 138 and further connections carries the circuit back to the storage battery 49.

5 The ignition switch 29 is provided with a second terminal 165 and by means of a lead wire 166 completes a connection from the ignition switch to one terminal 167 of the engine coil 56. The other terminal 168 of the coil 56 is joined by means of a lead wire 169 to a terminal 170 10 on the distributor 57. The distributor 57 is also provided with a ground 171.

A lead wire 172 is joined to the contact 78 on the micro-switch 66 and extends to one terminal 173 of the bell alarm 54. The other terminal 174 of the bell alarm is 15 grounded at 175. This then completes the electrical circuit as shown in FIGURE 5.

In the operation of the device of this invention the armored car is "at rest" with all of the doors locked from the inside and no personnel being within the armored car. 20 Let us assume that in operation the car is stored in a garage where such armored cars are kept. At the start of a shift when the crew arrives to take out the car the driver opens the cover 62 on the first control box 50 which as previously stated is the only one of the electrical elements 25 which is positioned outside of the two interior compartments 18 and 19. The pulling out of the front cover 62 of the box 50 in the direction of the arrow 75 as shown in FIGURE 2 acts to close the micro-switch contacts 77 and 78 with the cross bar 79 and thereby complete the circuit 30 to the small audible bell type alarm 54 disposed in the rear vault compartment 19 of the armored car. This alarm although not loud is sufficiently audible to alert other personnel in the garage that the crew is entering this particular armored car. If unauthorized personnel attempt 35 to enter the car in this manner they too would be noticed by this alarm 54. While the cover 62 is pulled forwardly from the body portion 58 of the box 50 the driver or other attendant attempting to gain entrance to the vehicle inserts a key 76 into the key switch 74 and this completes the 40 electrical circuit for the energizing of either of the solenoids 42 or 44 and causes an opening of either door 22 or door 23. The particular door to be opened by the insertion of the key 76 is controlled by the position of the toggle switch 73. In the position of the switch 73 as 45 shown in the circuit of FIGURE 5 the door 23 will open. When the driver wishes to gain access to his seat in the vehicle he moves the toggle switch 73 so that it completes the circuit to the contact 107 thus opening the door 22 by reason of the retraction of the lock bolt 41 and the actuation of the spring hinge 34 to automatically swing the door open slightly so that the driver can then pull the door 22 to an open position for climbing into the armored car. Immediately upon the door 22 being opened the driver then withdraws the key 76 from the key switch 74 and replaces the weatherproof front cover 62 of the control box 50 thereupon silencing the alarm 54 by causing an opening 50 of the micro-switch 66. The armored car is now ready for entrance by the driver, a guard and a messenger all as controlled by the person gaining access to the driver's seat 55. In his driving position the driver may reach and operate the control box 51 and open the other doors of the vehicle as desired. Each of the doors 22, 23, 24 and 25 may be operated from the control box 51 within the driver's compartment 18 provided that the master switch 95 which is the four pole-double throw switch on box 53 located in the vault compartment 19 is not swung to a position where the switches thereof are in engagement with the contacts 155, 146, 162a and 126. In this position 60 of the switch 95 the siren 55 is sounding and the doors 24 and 25 are locked against control by anyone in the front compartment 18. Still further the ignition switch 29 is disengaged so that no one may operate the vehicle. Therefore when the vehicle is at rest in storage position the master switch 95 is thrown so that it is in engagement 65 with the contacts 156, 147, 163 and 127. In this position 70

75 with the contacts 156, 147, 163 and 127. In this position

of the master switch the driver may open the doors 22, 23, 24 or 25 merely by actuating the switches 83, 84, 85 or 86. When all of the personnel are boarded and the doors closed from the inside the driver may then actuate the ignition switch 29 and start the armored car. If the driver is made aware of any danger of attack on the vehicle he may separately activate the electrical siren 55 by closing the switch 87.

However, a principal function of the present invention is to enable an occupant of the vault compartment to render immobile the vehicle and bar entrance to the vault compartment by any other control means as well as to energize the loud audible siren 55 merely by throwing one switch 95. It should thus be apparent that each of the three electrical boxes 50, 51, and 53 performs an important function in the overall operation of the security apparatus of this invention. The doors have no latch operating means immediately on their exteriors and even if a messenger or driver of the armored car is apprehended outside of the vehicle and the attackers somehow gain access to the driver's compartment whether by the key 76 in the switch 74 or otherwise they still cannot get into the valuables compartment nor can they move the armored car because the ignition has been cut. Also, all of this time the siren is blaring making it extremely difficult for felons to make a successful robbery.

It is intended that the armored car having the security device of this invention incorporated thereon shall be operated in the following typical situation. The armored car crew assembles in the garage of the armored car company or any bank or company using armored car vehicles in their business. The driver of the crew approaches the car and opens the cover on the weatherproof box 50 to commence a procedure intended to gain initial access to the car. The pulling of the cover 62 in the direction of the arrow 75 causes a closing of the microswitch 66 to complete an electrical circuit to the bell 54 in the rear compartment. The bell immediately commences ringing. The driver then inserts a key into the lock switch 74. By turning the key an electrical circuit is completed to either the solenoid 42 or 44 on door 22 or 23. The particular solenoid to be energized depends on the position of the toggle switch 73. If this toggle switch is in the position engaging the contact 107 then the driver's door 22 will open, but if the toggle switch is in the position to engage the contact 108 door 23 will open. This is primarily a safety feature in case of a failure of one of the solenoids on the two front doors. Now that the desired front door stands slightly open the driver removes the key from the switch 74 and closes the cover of box 50. This replacement of the cover opens the circuit to the solenoids and opens the bell circuit causing it to cease ringing. Now that the driver has gained access to the front compartment 18 he now has control of all four doors by use of the switches 83, 84, 85 and 86 all located on the control box 51 in the driver's compartment 18. The driver then closes door 22 behind him and actuates switch 84 to check the operation of solenoid 44 and to admit another front compartment crew member if the car carries a four man crew. The driver then admits a guard and a messenger through either of door 24 or 25 by actuating switch 85 or 86 which closes electrical circuit to solenoid 46 or 48 respectively. The guard and messenger load up the armored car and climb aboard and close doors 24 and 25 behind them. In a preferable procedure the guard throws switch 95 to close the circuit to the siren 55, open the circuit to the ignition shutting off the engine, and concurrently open the circuit to solenoids 46 and 48. Switch 95 as previously described is a four pole-double throw switch. The guard then turns off the switch 95 after seeing that everything functions properly. The driver then checks his siren switch 87 and restarts the engine and the armored car and crew have started their day's work. The entire circuit has thus been checked for any malfunction before the armored car and

its crew leave the storage garage. Most of the checking cannot be forgotten because it has to be done in order to gain access to the armored car. A complete operational check is thus simply done by actuating a number of switches.

Upon arrival at the first customer the guard and messenger exit through either door 24 or 25 by manually operating them from the inside or by actuating switch 93 or 94 on the control box 53 located in their vault compartment 19. Upon their return the driver presses switch 85 or 86 on the control box 51 located in his compartment to actuate solenoid 46 or 48 on door 24 or 25. The guard and messenger get in and close the doors behind them and the driver proceeds to the next customer. At the next stop the driver and messenger get out by manually operating their respective door locks or by the driver actuating switch 83 on box 51 for his exit through door 22 and the messenger actuating switch 93 or switch 94 for his exit out of either door 24 or 25.

Let us assume that while the driver and messenger are away from the armored car, felons attempt to steal the contents of the car. For example let us further assume that they have even acquired a key for operating the lock switch 74 in the external control box 50. With the key they intend entering through either front door 22 or 23 and drive the car containing the guard away, or as an alternative actuate the solenoid 46 or 48 and gain access to the rear compartment. However, as the felon opens the cover 62 to box 50 the circuit to the alarm bell 54 is closed and the guard is alerted before a key can be inserted into the key switch 74. All the guard has to do is simply throw alarm switch 95 and this performs the three functions as follows:

- (1) Starts siren 55 in operation alerting driver and messenger that the vehicle is being attacked;
- (2) Opens ignition circuit to prevent car from being driven away; and
- (3) Opens circuits to solenoids 46 and 48 on doors 24 and 25 making access to the rear compartment 19 impossible.

When the burglar flees and the driver and messenger return the guard turns off switch 95 and actuates the switches 91 and 93 to let the driver and messenger re-enter the armored car. The driver then restarts the engine and proceeds to the next stop.

In the event that the guard and messenger are away and someone tries to tamper with box 50 it would be noticed at once by the driver because of the location of box 50 in the center of the windshield in plain view of the driver. Someone would have to lean over the hood and fenders to reach it and this could hardly be unnoticed. Of course at this point the driver would actuate switch 87 to excite the loud siren 55. Also if there is a second guard seated next to the driver he would have equal access to the controls on box 51 located in the driver's compartment. Although it forms no direct part of the present invention it is desirable to have gun ports located on the front wall of the car as well as on each door preferably below the window. The armed crew can then defend themselves and ward off any attack by outsiders.

In certain existing armored cars it is oftentimes difficult to rescue a disabled crew member from one of the locked compartments whereas in the present device it is immaterial how the crew member becomes disabled, whether by car collision or illness, the doors to the compartment may be opened from other stations and the crew member removed. Similarly the vault contents may be quickly removed and saved if the car is in an accident and fire should start. The control boxes 51 and 53 are within easy reach of any crew member so that operation thereof is convenient and fast.

The above description of an example of the operation is merely suggestive and not necessarily required procedure. I am aware that numerous details of construction 75 may be varied throughout a wide range without departing

from the principles disclosed herein and I therefore do not propose limiting the patent granted hereon otherwise than as necessitated by the appended claims.

What is claimed is:

1. In an armored car of the type having a body defining a driver's compartment with a windshield on the front thereof and a separately armored rear vault compartment, said body having doors leading to the driver's compartment and to the vault compartment, a source of electricity, and a security apparatus for the armored car comprising, electric door locking solenoids on the inside of each door, at least one electrically actuated audible alarm, a first electrical control box mounted on said body outside of said compartments, a second electrical control box mounted within said driver's compartment, a third electrical control box mounted within said vault compartment, electrical circuit means joining said source of electricity with said first, second and third electrical control boxes, with said electric door locking solenoids, and with said electrically actuated audible alarm, and independently operable means on said first, second and third electrical control boxes for actuating certain of said electric door locking solenoids to effect opening of said doors and activating said electrically actuated audible alarm and whereby said three electrical control boxes and their electrical circuit means render the armored car substantially burglar-proof.

2. In an armored car of the type having a body defining a driver's compartment with a windshield on the front thereof and a separately armored rear vault compartment, said body having doors leading to the driver's compartment and to the vault compartment, a source of electricity, and a security apparatus for the armored car comprising, electric door locking solenoids on the inside of each door, at least one electrically actuated audible alarm, a first electrical control box mounted on said body outside of said compartments at a position visible through said windshield, a second electrical control box mounted within said driver's compartment, a third electrical control box mounted within said vault compartment, electrical circuit means joining said source of electricity with said first, second and third electrical control boxes, with said electric door locking solenoids, and with said electrically actuated audible alarm, and separate means on said first, second and third electrical control boxes for actuating said electric door locking solenoids to effect opening of said doors and activating said electrically actuated audible alarm.

3. In an armored car of the type having a body defining a driver's compartment with a windshield on the front thereof and a separately armored rear vault compartment, said body having doors leading to the driver's compartment and to the vault compartment, a source of electricity, and a security apparatus for the armored car comprising, electric solenoids on the inside of each door, at least one audible alarm, a first electrical control box mounted on said body outside of said compartments at a position substantially centrally of said windshield and immediately forwardly thereof, a second electrical control box mounted within said driver's compartment, a third electrical control box mounted within said vault compartment, electrical circuit means joining said source of electricity with said first, second and third electrical control boxes, with said electric solenoids, and with said audible alarm, and switch means on said first electrical control box providing the sole external means for controlling the opening of said doors by actuating said electric solenoids.

4. In an armored car having an armored front compartment and an armored rear compartment and an electrical security apparatus for controlling operation of the car's ignition system, access to the car, and actuation of alarms, comprising a first electrical control box mounted on the car exteriorly of the front and rear compartments, a second electrical control box mounted in said front

compartment, a third electrical control box mounted in said rear compartment, each of said compartments having hinged doors spring biased to normally swing open at least a small amount, electric solenoids on each of said doors, lock members on each of said solenoids arranged and constructed to hold said doors closed until the solenoids are energized whereupon the doors are opened, a first audible alarm mounted in said rear compartment, a second louder audible alarm positioned exteriorly of said front and rear compartments, an ignition system for said armored car, a source of electricity, and switch means on each of said electrical control boxes for controlling certain of said electric solenoids on said doors, for controlling the audible alarms, and for controlling the car ignition.

5. A device as set forth in claim 4 in which said first electrical control box is waterproof and is provided with an operable cover, first switch means operable in response to the cover removal to actuate the first alarm, second switch means to energize the front compartment door electric solenoids, and third switch means to optionally select the front compartment door to be opened.

6. A device as set forth in claim 4 in which said first electrical control box is waterproof and is provided with a translationally openable cover, spring means normally urging said cover toward closed position, first switch means operable in response to the cover opening to actuate the first alarm, second switch means to energize the front compartment door electric solenoids, and third switch means to optionally select the front compartment door to be opened.

7. A device as set forth in claim 4 in which said first electrical control box is waterproof and is provided with a cover adapted for slideable opening, means preventing cover rotation, first switch means operable to close in response to the cover opening to actuate the first alarm, second switch means operable to energize the front compartment door electric solenoids, and third switch means to optionally select the front compartment door to be opened.

8. In an armored car having an armored front compartment and an armored rear compartment and an electrical security apparatus for controlling operation of the car's ignition system, access to the car, and actuation of alarms, comprising a first electrical control box mounted on the car exteriorly of the front and rear compartments, a second electrical control box mounted in said front compartment, a third electrical control box mounted in said rear compartment, each of said compartments having hinged doors spring biased to normally swing open at least a small amount, electric solenoids on each of said doors, lock members on each of said solenoids arranged and constructed to hold said doors closed until the solenoids are energized whereupon the doors are opened, a first audible alarm mounted in said rear compartment, a second louder audible alarm positioned exteriorly of said front and rear compartments, an ignition system for said armored car, a source of electricity, and switch means on the first of said electrical control boxes providing the sole means outside of the interior of the compartments for controlling certain of said electric door solenoids.

9. In an armored car having an armored front compartment and an armored rear compartment and an electrical security apparatus for controlling operation of the car's ignition system, access to the car, and actuation of alarms, comprising a first electrical control box mounted on the car exteriorly of the front and rear compartments, a second electrical control box mounted in said front compartment, a third electrical control box mounted in said rear compartment, each of said compartments having hinged doors spring biased to normally swing open at least a small amount, electric solenoids on each of said doors, lock members on each of said solenoids arranged and constructed to hold said doors closed until

the solenoids are energized whereupon the doors are opened, a first audible alarm mounted in said rear compartment, a second louder audible alarm positioned exteriorly of said front and rear compartments, an ignition system for said armored car, a source of electricity, switch means on each of said electrical control boxes for controlling certain of said electric door solenoids, for controlling the audible alarms, and for controlling the car ignition, and the third of said electrical control boxes having a master switch therein to bar opening of the doors to the rear compartment from either of the other two boxes.

10. In an armored car having an armored front compartment and an armored rear compartment and an electrical security apparatus for controlling operation of the car's ignition system, access to the car, and actuation of alarms, comprising a first electrical control box mounted on the car exteriorly of the front and rear compartments, a second electrical control box mounted in said front compartment, a third electrical control box mounted in said rear compartment, each of said compartments having hinged doors spring biased to normally swing open at least a small amount, electric solenoids on each of said doors, lock members on each of said solenoids arranged and constructed to hold said doors closed until the solenoids are energized whereupon the doors are opened, a first audible alarm mounted in said rear compartment, a second louder audible alarm positioned exteriorly of said front and rear compartments, an ignition system for said armored car, a source of electricity, said first electrical control box having switch means to control the energizing of the front compartment door electric solenoids and the first alarm in the rear compartment, said second electrical control box having switch means to control the energizing of the front and rear compartment door electric solenoids and the second alarm, and the third electrical control box having switch means to control the energizing of the front and rear compartment door electric solenoids and a master switch to prevent energizing of the rear compartment door solenoids, to cut out the car ignition system, and to actuate the second alarm.

11. In an armored car having an armored front compartment and an armored rear compartment and an electrical security apparatus for controlling operation of the car's ignition system, access to the car, and actuation of alarms, comprising a first electrical control box mounted on the car exteriorly of the front and rear compartments, a second electrical control box mounted in said front compartment, a third electrical control box mounted in said rear compartment, each of said compartments having hinged doors spring biased to normally swing open at least a small amount, electric solenoids on each of said doors, lock members on each of said solenoids arranged and constructed to hold said doors closed until the solenoids are energized whereupon the doors are opened, a first audible alarm mounted in said rear compartment, a second louder audible alarm positioned exteriorly of said front and rear compartments, an ignition system for said armored car, a source of electricity, said first electrical control box having separate switch means to control the energizing of the front compartment door electric solenoids and the first alarm in the rear compartment, said second electrical control box having separate switch means to control the energizing of the front and rear compartment door electric solenoids and the second alarm, and the third electrical control box having separate switch means to control the energizing of the front and rear compartment door electric solenoids and a master switch to prevent energizing of the rear compartment door solenoids at either of the first or second electrical control boxes, to cut out the car ignition system, and to actuate the second alarm.

12. In an armored car having a body, said body having an armored front driver's compartment with a view-

ing windshield in the front thereof and an armored rear vault compartment, an electrical security apparatus for controlling operation of the car's ignition system, access to the car, and actuation of alarms, comprising a first electrical control box mounted on the body forwardly of the windshield of the front compartment, a second electrical control box mounted in said front driver's compartment, a third electrical control box mounted in said rear vault compartment, each of said compartments having hinged doors spring biased to normally swing open at least a small amount, electric solenoids on each of said doors, lock members on each of said solenoids arranged and constructed to hold said doors closed until the solenoids are energized whereupon the doors are opened, a first audible alarm mounted in said rear compartment, a second louder audible alarm positioned exteriorly of said front and rear compartments, an ignition system for said armored car, a source of electricity, said first electrical control box having the sole switch means to control the energizing of the front compartment door electric solenoids from outside the front and rear compartments and the first box having further switch means to energize the first alarm in the rear compartment, said second electrical control box having switch means to control the energizing of the front and rear compartment door electric solenoids and the second alarm, and the third electrical control box having switch means to control the energizing of the front and rear compartment door electric solenoids and a master switch to prevent energizing of the rear compartment door solenoids, to cut out the car ignition system, and to actuate the second alarm.

13. An armored car comprising a body, said body defining front and rear compartments, said front compartment having a transparent windshield in the front thereof, a plurality of doors in each of said compartments, electric solenoid operated lock means associated with the interior of each door, control means mounted on the outside of said body at a position forwardly of and viewable through said windshield and remote from any door for optionally effecting energization of any one of the electric solenoid operated lock means associated with the doors in the front compartment, and control means within said body for effecting energization of all of said electric solenoid operated lock means.

14. An armored car comprising a body defining an interior and an exterior, the interior of said body having a bulkhead disposed generally transversely of the length of the car and dividing the interior into a front compartment and a rear compartment, a door in said body leading to said front compartment, a door in said body leading to said rear compartment, lock means on each of said doors, electric solenoids associated with each door lock means and operated thereby to lock or unlock the doors, a first control means mounted on the exterior of the body spaced from any door for effecting energization of the solenoid on said door leading to the front compartment, a second control means mounted within the front compartment for separately effecting energization of the solenoids on both the door leading to the front compartment and the door leading to the rear compartment, and a third control means mounted within the rear compartment for separately effecting energization of the solenoids on both the door leading to the rear compartment and including means rendering the energization of the solenoid on the door leading to the rear compartment ineffective from the second control means in the front compartment.

15. In a substantial burglar-proof armored car of the type having an armored body defining an interior compartment, doors opening into said interior compartment, a source of electricity, and a security apparatus for the armored car comprising electric solenoids on the inside of each door, lock bolts on each of said doors operable by said electric solenoids, a first audible alarm mounted

in said interior compartment, a second louder audible alarm mounted on said car outside of said interior compartment, an exteriorly mounted electrical control box for actuating selected door electric solenoids to effect opening of said doors and to simultaneously actuate said first audible alarm, and an interiorly mounted electrical control box for actuating said door electric solenoids and for optionally actuating said second louder audible alarm.
